PAGE 2

Fig. 3

Fig. 4

Fig. 5

FIGURE 1 is a top plan view of a catamaran showing our new design.

FIGURE 2 is a bottom plan view of the catamaran.

FIGURE 3 is a side elevational view of the catamaran.

FIGURE 4 is a front elevational view of the catamaran.

FIGURE 5 is a fragmentary perspective view of the catamaran taken from the rear.

FIGURE 6 is an enlarged sectional view taken substantially along the line 6-6 of FIG. 1 as viewed in the direction indicated by the arrows.

FIGURE 7 is a sectional view taken substantially along the line 7-7 of FIG. 1 as viewed in the direction indicated by the arrows.

The dominant features of our design reside in the portions thereof shown in full lines.

We claim:

The ornamental design of a catamaran, as shown and described.
